UNITED STATES PATENT OFFICE.

WILLIAM N. KIDDER, OF PROVIDENCE, RHODE ISLAND.

ARTIFICIAL TOOTH.

1,108,449.

Specification of Letters Patent. Patented Aug. 25, 1914.

Application filed September 2, 1913. Serial No. 787,563.

To all whom it may concern:

Be it known that I, WILLIAM N. KIDDER, a citizen of the United States, residing at Providence, in the county of Providence and State of Rhode Island, have invented certain new and useful Improvements in Artificial Teeth, of which the following is a specification.

My invention relates to artificial teeth, and more especially to the construction of metal backing plates therefor arranged to be secured to porcelain crowns or fronts.

In the accompanying sheet of drawings, Figure 1 represents a front elevation of my improved tooth; Fig. 2 is a back elevation of the same (the metal backing or anchor plate removed); Fig. 3 is a side elevation, corresponding with Fig. 2; Fig. 4 is an enlarged perspective view of the metal key, disconnected from the back of the porcelain facing; Fig. 5 is a vertical section, enlarged, taken through the center of my improved tooth, showing the porcelain facing portion rigidly secured to the metal backing plate, and also showing the manner of connecting the parts; Fig. 6 is a perspective view, showing the backing plate detached from the front porcelain member; Fig. 7 is an enlarged cross-section, taken on line 7—7 of Fig. 1; Fig. 8 shows a rear elevation of the untrimmed backing plate, formed from comparatively thin metal stock; the recessed cavity itself being the exact counterpart of and adapted to snugly receive the metal key fixed to the back of the porcelain facing; Fig. 9 is a cross-section of the plate, taken on line 9—9 of Fig. 8; and Fig. 10 is a side elevation, showing a manner of securing my improved tooth crown to a natural tooth-root retained in the jaw.

In the drawings: α designates a porcelain facing or artificial crown having a plurality of metal pins p , as platinum, embedded and baked therein and extending at substantially right angles from the rear plane face α^1 and forming a well-known article of manufacture, said crown usually having an endwise extension α^2 which is or may be ground off when the facing member is employed in connection with certain dental operations. Crowns of such construction are stronger and very much less liable to become accidentally broken than porcelain facing mem-

bers in which the lugs or recesses are formed integral therewith.

In my improved artificial tooth construction I employ an apertured metal block b , which may be termed a key or gib, the same having oppositely facing plane and inclined sides b^1 , b^2 , and opposed dovetail lateral edges b^3 ; in practice these blocks are alike and interchangeable, Fig. 4. The pins p of the porcelain facings are inserted in the apertures p^1 of the blocks and permanently secured thereto by riveting or soldering. As thus constructed, each of the block-carrying facings or crowns is a duplicate of the others in the respective classes of crowns.

An essential feature of the invention consists in providing a metal backing-plate c having a recess d adapted to readily receive the said block or key member b extending from the back of the porcelain facing. The said recessed plates or units c may be duplicates of one another and swaged from sheet metal, as gold; the base part or flange is somewhat larger than required in order to allow for trimming, variations in size, etc., substantially as shown in Figs. 8 and 9. The recessed part d , however, is an exact counterpart of the said key b ; that is, the inclined sides c^2 , d^2 , d^3 conform accurately to the respective sides b^2 , b^3 , b^3 of the key. Thus, it is obvious that a porcelain tooth or crown α having a plane rear face α^1 to which is fixed the metal key element b may be taken indiscriminately from a mass of similarly provided teeth and be readily interlocked with one of the said metal backing plates c by simply inserting the key into the cavity d until the faces α^1 and c^1 engage each other, say at the point m , as indicated in dotted lines, Fig. 5; at the same time pressing the plate in the arrow direction 1, thereby causing the latter to swing outward, see arrow 2. the action of the undercut or dovetailed edges b^2 , d^2 , meanwhile guiding the lower or thinner end of the wedge part inward (see arrow 3) until the parts b and d snugly engage each other. At the same time, too, the lower or incisive edge α^3 of the porcelain crown is protected by the edge c^3 of the plate c , as indicated in said Fig. 5.

In my improved metal plate or back the recess d formed therein is closed on all

sides, thereby completely covering, protecting and concealing the gib-block, thus preventing the entrance of injurious foreign matter, the action of which latter would 5 tend to shorten the life of the tooth.

By means of my improvement the incisive edge c^3 of the plate may be inturned or shaped and fitted and readily attached to the crown and gib, see Fig. 5, wherein the 10 plate is represented as being swung downward and inward preliminary to placing the plate in its fixed position.

A manner of mounting a tooth, constructed according to my invention, to a suitably 15 prepared natural root r , is represented in Fig. 10. The extension a^2 of the porcelain facing a is first ground off even with the corresponding end of the backing plate c , followed by soldering a cupped flange h thereto 20 adapted to receive the adjacent end of the root; the latter is provided with an enlarged longitudinally extending cavity, into which cavity a metal post h^1 , secured to the flange h , is fixedly inserted. It may be added that 25 the several contiguous faces where the parts are joined are or may be suitably cemented together in a well-known manner. I prefer to also cement the key b into the wedge-shaped interlocking recess d of the backing 30 plate c . In order to render the inner surface of the plate smooth and symmetrical, or

semi-oval cross-sectionally, substantially as represented in Fig. 7, the same may be effected or built up by flowing gold solder over the surface to the desired extent. 35

I claim:

1. A metal backing member for artificial teeth, the same comprising a plate having a dovetail recess therein forming a seat arranged to receive and support a metal gib 40 or block element fixed to an artificial tooth, said recess being closed on all sides and adapted to cover and completely conceal said element when the latter is seated in the recess. 45

2. In an artificial tooth, the combination of a porcelain facing or crown member, a metal gib-block rigidly secured to the back race of the crown, said gib having a dovetail form and being materially thicker at the 50 root end than at the incisive portion of the crown, and a metal backing plate having a recess therein the counter-part of said gib, in which recess said gib is firmly seated, said recess being closed on all sides and completely concealing and protecting the gib. 55

In testimony whereof I have affixed my signature in presence of two witnesses.

WILLIAM N. KIDDER.

Witnesses:
